INDUCTIVELY COUPLED BAND-PASS FILTER

Madison Cawein, Fort Wayne, Ind., assignor, by
mesne assignments, to Farnsworth Research
Corporation, a corporation of Indiana

Application October 30, 1944, Serial No. 561,063

8 Claims. (Cl. 178—44)

1

This invention relates to band pass filters and particularly to a composite inductively coupled filter arranged for passing a broad band with substantially uniform response.

For modulated carrier receivers in the radio and television field band pass filters are required which are able to pass a wide band of frequencies with substantially uniform gain, while having a sharp cutoff outside of the desired pass band. Numerous filters have been designed for this purpose. However, unless a fairly complex network is utilized requiring a comparatively large number of filter elements a wide band filter usually shows less amplification in the middle of the band than at the edges thereof. This non-uniform response of the band pass filter can be compensated by providing two or more amplifier stages coupled by suitable coupling networks, each stage and its associated network being carefully designed to provide for a uniform overall response. However, in this case at least two amplifier stages are required for providing a uniform gain of the wide pass band to be transmitted.

The band pass filter of the invention has particularly utility as a broad-band filter having a substantially uniform flat response over the desired pass band. It may be used, for instance, in connection with intermediate frequency or constant frequency amplifiers.

It is an object of the present invention, therefore, to provide a composite band pass filter arranged for obtaining a broad-band flat response.

A further object of this invention is to provide an optimum-coupled band pass filter where broad-band resonant impedances are over-coupled to obtain a broader pass band with a substantially uniform response without requiring electronic coupling or other compensating means.

Another object of the invention is to provide an inductively coupled band pass filter having a selectivity outside of the band pass filter equivalent to that of four resonant circuits.

In accordance with the invention there is provided a composite band pass filter comprising two identical filter sections. Each of the two filter sections includes two identical resonant circuits and, hence, the band pass filter comprises four such resonant circuits. Each of the resonant circuits has a capacitance element and two inductance elements. One of the inductance elements is common to two of the resonant circuits for providing a self-inductive coupling therebetween. These two common inductance elements are inductively coupled to each other.

2

Preferably, the two common inductance elements are over-coupled with a mutual inductive coupling to provide for a broad-band substantially flat response.

For a better understanding of the invention, together with other and further objects thereof, reference is made to the following description, taken in connection with the accompanying drawing, and its scope will be pointed out in the appended claims.

In the accompanying drawing, Fig. 1 is a circuit diagram of a composite band pass filter embodying the present invention and utilized as an intermediate frequency or constant frequency filter in a radio receiver, while Fig. 2 is a set of curves illustrating the relative response plotted against the relative frequency of the filter of the invention.

Referring now more particularly to Fig. 1 of the drawing, there is shown a composite band pass filter in accordance with the invention utilized in a modulated carrier radio receiver. The receiver illustrated is of the superheterodyne type and includes antenna 1 connected to ground through coil 2. Coil 3, inductively coupled to coil 2, is connected to a radio frequency amplifier and intermediate frequency converter shown diagrammatically at 4. The output of radio frequency amplifier and intermediate frequency converter 4 is connected by lead 5 to band pass filter 6. The output of the band pass filter 6 is connected through lead 7 to intermediate frequency amplifier 8. Band pass filter 6 is coupled to the intermediate frequency converter 4 through blocking condenser 10. Connected in cascade to intermediate frequency amplifier 8 is second detector 12, audio amplifier 13 and loud speaker 14. The portions of the receiver described above, with the exception of band pass filter 6, may all be of conventional well-known construction so that detailed illustrations and descriptions thereof are deemed to be unnecessary.

Band pass filter 6 embodying the present invention includes two identical filter sections 15, 16. Filter section 15 comprises two identical resonant circuits. The first resonant circuit includes shunt condenser 20, series coil 21 and shunt coil 22. The second resonant circuit which is identical to the first circuit includes shunt condenser 23, series coil 24 and shunt coil 22. Hence, it will be seen that shunt coil 22 is common to the two resonant circuits just described and provides a self-inductive coupling therebetween.

Filter section 16 is identical with filter section 15 and also includes two identical resonant cir-

cuits. The first resonant circuit of filter section 16 includes shunt coil 25, shunt condenser 26 and series coil 27, while the second resonant circuit consists of shunt condenser 28, shunt coil 25 which is common to the two resonant circuits and series coil 30. Filter sections 15 and 16 are mutually inductively coupled through shunt coils 22 and 25. Series coils 21, 24, 27 and 30 are not inductively coupled to each other as indicated by shield 31 illustrated between series coils 24 and 27; if desired a similar shield may be arranged between series coils 21 and 24 and between series coils 27 and 30.

The band pass filter of the invention consists of four identical circuits which are all tuned to the same resonant frequency. The response curve of a composite band pass filter of this type depends mainly upon the mutual inductive coupling between coils 22 and 25. The optimum coupling which will give a substantially uniform broad-band response with a good selectivity outside of the pass band can be calculated in the following manner. We will assume that each of condensers 20, 23, 26 and 28 has the same capacitance value C. We will also assume that each of series coils 21, 24, 27 and 30 has the same inductance value L. The inductance of each of coils 22 and 25 is assumed to be identical and has the value M. The mutual inductive coupling between coils 22 and 25 is M'.

We define now

$$K = \frac{M}{L}$$

$$s = \frac{M'}{M}$$

and

$$p = \frac{1}{Q}$$

Q is the ratio of the reactance over the resistance of any one of series coils 21, 24, 27 and 30. Its value may be determined by

$$Q = 2\pi f_0 \frac{L}{R}$$

where R is the ohmic resistance of any one of the four series coils of the band pass filter, and f_0 is the resonant frequency of any of the four resonant circuits. If a load resistor is connected to any one of the four resonant circuits, its resistance should be included in the value of R for a calculation of Q for that series coil. In that case it may be necessary to provide additional resistances for the other series coils so that the Q of all four series coils 21, 24, 27 and 30 will be equal.

We will now assume that $K=p$ which means that

$$\frac{M}{L} = \frac{1}{Q}$$

With this assumption the relative response A of the band pass filter of the invention can be calculated, and the result is as follows:

$$A = \frac{cs}{\sqrt{[4p^4 + (s+x)^4][4p^4 + (s-x)^4]}}$$

In this formula c is a constant and

$$x = 2\frac{f-f_0}{f_0}$$

f_0 being the resonant frequency and f a variable

frequency. The resonant frequency may be obtained by the following relationship:

$$f_0 = \frac{1}{2\pi\sqrt{C(L+M)}}$$

The above formula can be rewritten by dividing the nominator and denominator by p^2 . Hence,

$$A = \frac{cs'/p}{\sqrt{[4 + (s'+x')^4][4 + (s'-x')^4]}}$$

which can be transformed into

$$\frac{Ap}{c} = \frac{s'}{\sqrt{[4 + (s'+x')^4][4 + (s'-x')^4]}}$$

15 In this formula

$$s' = \frac{s}{p}$$

and

$$x' = \frac{x}{p}$$

This equation can be solved for x' when s' is treated as a parameter. In this manner a family of curves can be obtained, and x' , the relative frequency can be plotted against

$$\frac{Ap}{c}$$

the relative response. p may be treated as a constant because it depends upon f_0 , the resonant frequency which is constant. For $f=f_0$, $x'=0$. Furthermore, the formula for the relative response is symmetrical in x' ; changing the sign of x' will not change the value obtained for A.

It will be appreciated that the above calculations are greatly facilitated because the band pass filter of the invention includes four identical resonant circuits. Besides, the type of coupling between the circuits is particularly simple. Calculation of a quadruply-tuned circuit without the assumption of suitable simplifications presents almost unsurmountable difficulties.

Fig. 2 illustrates the relationship between the relative frequency x' and the relative response

$$\frac{Ap}{c}$$

It will be seen that for $s'=2$ the relative response is substantially uniform over a fairly broad range while the selectivity outside of the pass band is high corresponding to that of four resonant circuits. With a value of $s'=2.25$ the response is still fairly uniform. Optimum coupling is, therefore, obtained with a coupling value of s' between 2 and 2.25. This can be interpreted in the following manner:

$$s' = \frac{s}{p}$$

therefore,

$$s = ps' = \frac{M'}{M} = \frac{M}{L} s'$$

By substituting the optimum value for s' as explained hereinabove M' can be calculated.

In order to design a band pass filter in accordance with the invention the following procedure may be adopted. At first a value for resonant frequency f_0 , and for L the inductance of any one of coils 21, 24, 27 and 30 should be chosen. Then, the inductance of coils 22 and 25 may be calculated as follows:

$$\frac{M}{L} = \frac{1}{Q} = \frac{R}{2\pi f_0 L}$$

Hence,

$$M = \frac{R}{2\pi f_0}$$

the capacitance of condensers 20, 23, 26 and 28 may be determined from the following equation:

$$f_0 = \frac{1}{2\pi\sqrt{C(L+M)}}$$

or

$$C = \frac{1}{(2\pi f_0)^2(L+M)}$$

Now, M' may be determined from the following relationship:

$$\frac{M'}{M} = \frac{M}{L} s'$$

and, therefore,

$$M' = \frac{M^2}{L} s'$$

which in turn can be expressed as follows:

$$M' = \frac{s' R^2}{(2\pi f_0)^2 L}$$

The band pass filter of the invention has been shown as the coupling filter between intermediate frequency converter 4 and intermediate frequency amplifier 8. If more than one intermediate frequency amplifier stage is provided, the band pass filter of the invention may be arranged between every two subsequent stages. Blocking condenser 10 serves to separate the direct current from the plate circuit of the last tube of radio frequency amplifier and intermediate frequency converter 4 from the input circuit of intermediate frequency amplifier 8. However, it is to be understood that blocking condenser 10 forms no part of band pass filter 6.

It is true that the band pass filter of the invention operates only accurately at a predetermined frequency. However, it will function reasonably well within a certain frequency range. To this end condensers 20, 23, 26 and 28 may all be made variable and ganged together so that the resonant frequency f_0 will be adjustable within a certain range. The numerical values of the circuit elements should be calculated in accordance with the above formulas for the mid-frequency of this range. Thus a certain adjustment of the resonant frequency may be provided.

Referring briefly to the operation of the superheterodyne radio receiver illustrated in Fig. 1, modulated carrier signals intercepted by antenna 1 are coupled by means of coils 2 and 3 to radio frequency amplifier and intermediate frequency converter 4. Here, the intercepted signal is amplified and converted into an intermediate frequency signal. The intermediate frequency signal derived from converter 4 is coupled to band pass filter 6 through coupling condenser 10. Band pass filter 6 passes the intermediate frequency signal with its side bands to intermediate frequency amplifier 8. The intermediate frequency is amplified in amplifier 8 and connected in turn to detector stage 12. The modulation components of the signal are derived from detector stage 12 and are amplified by audio amplifier 13 from which they are supplied in the usual manner to loud speaker 14.

While there has been described what is at present considered the preferred embodiment of the invention, it will be obvious to those skilled in the art that various changes and modifications may be made therein without departing from the invention, and it is, therefore, aimed in the appended claims to cover all such changes and modi-

fications as fall within the true spirit and scope of the invention.

What is claimed is:

1. A composite band pass filter comprising two identical filter sections, each of said filter sections including two identical resonant circuits, each of said resonant circuits having a capacitance element and two inductance elements, one of said inductance elements being common to two of said
- 5 16 circuits for providing a self-inductance coupling therebetween, said two common inductance elements being inductively coupled to each other.
- 17 2. A composite band pass filter comprising two identical filter sections, each of said filter sections including two identical resonant circuits, each of said resonant circuits having a capacitance element and two inductance elements, one of said inductance elements being common to two of said
- 21 20 circuits for providing a self-inductive coupling therebetween, said two common inductance elements being over-coupled with a mutual inductive coupling thereby to provide for a broadband substantially flat response, means for supplying an input signal across a capacitance element of one of said filter sections, and means for deriving an output signal across a capacitance element of the other one of said filter sections.
- 25 3. A composite band pass filter comprising two identical filter sections, each of said filter sections including two identical resonant circuits, each of said resonant circuits having a capacitance element and two inductance elements, one having an inductance L and the other one having an inductance M , said inductance element having an inductance M being common to two of said
- 30 35 circuits for providing a self-inductive coupling therebetween, said two common inductance elements having the inductance M being coupled to each other with a mutual inductive coupling M' so that

$$\frac{M'}{M}$$

has a value substantially between

$$2 \frac{M}{L}$$

and

$$2.25 \frac{M}{L}$$

- 45 50 5. A composite band pass filter comprising two identical filter sections, each of said filter sections including two identical resonant circuits, each of said resonant circuits having a capacitance element and two inductance elements one having an inductance L and the other one having an inductance M , said inductance element having the inductance M being common to two of said
- 55 60 circuits for providing a self-inductive coupling therebetween, said two common inductance elements having the inductance M being coupled to each other with a mutual inductive coupling M' so that

$$\frac{M'}{M}$$

has a value substantially between

$$2 \frac{M}{L}$$

and

$$2.25 \frac{M}{L}, \frac{M}{L}$$

being equal to

$$\frac{1}{Q}$$

where Q is the ratio of the reactance over the resistance of any one of said inductive elements having the inductance L , means for supplying an input signal across a capacitance element of one of said filter sections, and means for deriving an output signal across a capacitance element of the other one of said filter sections.

5. A composite band pass filter comprising two identical filter sections, each of said filter sections including two identical resonant circuits, each of said resonant circuits having a capacitance element and an inductance element connected in parallel and another inductance element connected in series, said series inductance element being common to two of said circuits for providing a self-inductive coupling therebetween, said two common inductance elements being inductively coupled to each other.

6. A composite band pass filter comprising two identical filter sections, each of said filter sections including two identical resonant circuits, each of said resonant circuits having a capacitance element and an inductance element connected in parallel and another inductance element connected in series therebetween, said series inductance element being common to two of said circuits for providing a self-inductive coupling therebetween, said two common inductance elements being optimum-coupled to each other with a mutual inductive coupling therebetween to provide for a broad-band substantially flat response, means for supplying an input signal across a capacitance element of one of said filter sections, and means for deriving an output signal across a capacitance element of the other one of said filter sections.

7. A composite band pass filter comprising two identical filter sections, each of said filter sections including two identical resonant circuits, each of said resonant circuits having a capacitance element and an inductance element having an inductance L connected in parallel and another inductance element having an inductance M connected in series therebetween, said induct-

8. ance elements having the inductance M being common to two of said circuits for providing a self-inductive coupling therebetween, said two common inductance elements having the inductance M being coupled to each other with a mutual inductive coupling M' so that

$$\frac{M'}{M}$$

has a value substantially between

$$2\frac{M}{L}$$

and

$$2.25\frac{M}{L}, \frac{M}{L}$$

being equal to

$$\frac{1}{Q}$$

where Q is the ratio of the reactance over the resistance of any one of said inductive elements having the inductance L , means for supplying an input signal across a capacitance element of one of said filter sections, and means for deriving an output signal across a capacitance element of the other one of said filter sections.

8. A composite band pass filter comprising two identical filter sections, each of said filter sections including two identical resonant circuits, every two of said identical resonant circuits having a common inductance element for providing a self-inductive coupling therebetween, said common inductance elements being inductively coupled to each other.
